METHOD AND APPARATUS FOR REMOVING
STRINGER SCOOPSLouis H. Morin, Bronx, N. Y., assignor of one-half
to Davis Marinsky, Bronx, N. Y.

Application May 16, 1944, Serial No. 535,894

17 Claims. (Cl. 164—17)

This invention relates to separable fastener stringers comprising an elongated tape or strand with scoops spaced longitudinally of one edge thereof. More particularly, the invention relates to an apparatus for removing end scoops from a stringer in order to produce on the stringer a predetermined scoop length governed by the number of scoops on the tape of the stringer. Further, the invention comprises a novel method of removing end scoops, as more fully hereinafter set forth. The novel features of the invention will be best understood from the following description when taken together with the accompanying drawing in which certain embodiments of the invention are disclosed, and in which the separate parts are designated by suitable reference characters in each of the views; and in which:

Fig. 1 is a sectional view through a part of a stringer tape adjacent one scoop thereof, showing a part of two-scoop supporting and backing members and the tool for splitting the scoop to facilitate removal thereof from the stringer tape.

Fig. 2 is a sectional view through removal tools which I employ, shown detached with respect to one end of a stringer.

Fig. 3 is a view similar to Fig. 2, showing the tools in position engaging the stringer scoop, in the manner illustrated in Fig. 1 of the drawing.

Fig. 4 is a view similar to Figs. 2 and 3, showing the parts of the apparatus in a different position with the scoop halves removed from the stringer tape; and

Fig. 5 is a view similar to Fig. 3, showing another form of construction.

In the construction of separable fasteners, the stringers are usually produced in predetermined standard lengths. Oftentimes, in these standard lengths, it is essential to remove one or two end scoops in order to bring the stringer or the scoop length of the stringer to a very specific size. In casting scoops two or three at a time, this removal operation is particularly desirable, and in such instances, removal of one or two links may often-times be found necessary. There are still other cases where particular scoop lengths of a stringer are not available in stock, and where prompt deliveries are necessary, one standard length having an excessive number of scoops thereon may be used, and the excess scoops removed much quicker than it would be possible to cast the required number of scoops in making the machine changes to run off the specific required stringer lengths.

To satisfy the above requirements, I have conceived a simple apparatus as well as a simple

method whereby one or two end scoops may be quickly and easily split and then pulled away from the surfaces of the stringer tape in producing stringers of the required scoop length. In referring to scoop lengths, it will be apparent that reference is made to that portion of the stringer to which the scoops are attached, and is usually measured by the number of scoops arranged on the stringers.

10 The present invention deals more particularly with scoops of what might be termed angular or V-shaped cross sectional contour, such as disclosed for example, in my prior application Serial Number 531,618, and in Figs. 1 to 4 inclusive is shown one adaptation of the invention.

In said figures, 10 represents a part of a stringer tape upon which is arranged a predetermined number of scoops 11 governing the stringer scoop length. In Figs. 2, 3 and 4, only one end portion 5 of the stringer is shown with a few scoops thereon and illustrated in these figures is apparatus for, and a method of removing one end scoop, for example, the end scoop 11—a.

At 12 and 13 is shown a pair of scoop engaging 25 jaw members, each having sockets 14 at adjacent ends thereof conforming in general cross sectional contour to the contour of the mounting end portion 15 of the scoop, note Fig. 1 of the drawing. From this figure, it will also appear that the

20 sockets 14 open outwardly through the upper surface 16 of the jaws 12 and 13, and this surface of the jaws adjacent the bevelled ends 17 thereof, have knife kerfs 18 for receiving the pointed end 19 of a cutter blade 20, note Fig. 1 of the drawing. This arrangement is such that the sharp edge 19 30 of the blade will terminate at the bead 21 of the tape 10 without injury to the tape, and yet completely subdivide the scoop 11—a into two halves 22 and 22—a, which can then be pulled away from 35 opposite side surfaces of the tape 10 including the bead 21, in the manner illustrated in Fig. 4 of the drawing.

The jaw members are mounted to move angularly in carriages 23 and 24 which also form tools 45 for pulling the scoop halves 22 and 22—a away from the tape, as later described. Suitable guides 25 and 26 are provided for the carriages or tools 23 and 24 to provide back and forth movement thereof, in the manner illustrated diagrammatically in Figs. 2 to 4 inclusive, whereas suitable means is provided for moving the jaw members 12 and 13 independent of the carriages 23 and 24.

Considering Fig. 2 of the drawing, with the 50 parts in the open position, one end portion of

a stringer is supported between the jaw members 12 so that the sockets 14 of these jaw members will pass freely onto the side portions of the end scoop 11—a by movement of the jaw members 12 and 13 inwardly toward each other, the result of which operation is seen in Fig. 3 of the drawing. In this operation, the carriages 23 and 24 remain stationary in the position shown in Fig. 2 of the drawing. The blade 20 is then moved downwardly upon the end link 11—a, splitting the outer coupling end portion 21 of the scoop in the manner illustrated in Fig. 1, thus dividing the scoop into the separate parts 22 and 22—a.

With the parts in this position, the carriages 23 and 24 are then moved outwardly or away from the tape 10, the tape 10 being held stationary in this operation. As a result, the two scoop halves 22 and 22—a will be drawn from the opposite sides of the tape 10, including the beaded edge 21 thereof, and may thus be removed. Removal can take place by returning the carriages 23 and 24, and the jaw members 12 and 13 to the position as seen in Fig. 2 of the drawing. In this operation, the scoop halves 22 and 22—a will be automatically ejected from the sockets 14.

The construction diagrammatically illustrated in Figs. 2, 3 and 4, may be said to comprise a single blade apparatus, and if it is required to remove two or more end scoops, the tape may simply be fed into position to bring the next end scoop in position for removal, and the operation repeated as often as necessary. In referring to the above it will be understood that trimming operations may be performed on independent stringer lengths, and also on endless fastener members where the tape has not been severed to form the independent stringer lengths. In such latter instances, the tape will be automatically moved or fed through the shearing or removal apparatus for the purposes stated.

In Fig. 5 of the drawing I have shown an apparatus wherein two blades similar to the blade 20 will be used to simultaneously cut off two end scoops 28 and 29 similar to the scoops 11—a, but here the operation is shown as being performed at the other end of the stringer, simply to illustrate that scoops may be cut from either end of a stringer. In the construction shown in Fig. 5, I simply employ two jaw members 30 and 31 which are more or less similar to the carriages 23 and 24, omitting of course, the jaw members 12 and 13. In other words, here the carriage like jaw members 31 have on inner adjacent surfaces sockets or recesses 32 adapted to engage both of the scoops 28 and 29. The members 30 and 31 are slidably mounted in suitable supports 33 and 34, similar to the supports 25 and 26. With this construction, the stringer tape 35 upon which the scoops 28 and 29 are mounted, will in the open position of the members 30 and 31, indicated in dotted lines in Fig. 5, be arranged with the side edges of the scoops in alinement with the inner open ends of the socket 32, and as the members 30 and 31 move inwardly, the stringer 35 is moved downwardly. However, after the tools split the scoops 28 and 29 into independent halves 36 and 37, the tape 35 is held stationary and the members 30 and 31 are separated, which operation will remove the scoop halves 36 and 37, the same as is taught in Fig. 4 of the drawing.

The present invention is applicable to scoops attached to stringers in any desired manner, and

particularly when the scoops are die cast on the stringers, or in other words, are in the form of die cast bodies. This operation tends to establish a slight adhesion of the scoops to the surfaces of the stringer tape, which will require the separate scoop halves to be pulled away from the tape. It will also be understood that the invention is applicable to scoops cast from metal as well as from plastic materials.

From a consideration of Fig. 1 of the drawing, it will be apparent that in the shearing operation of the tool 20, the scoop or scoops are not only firmly supported in upright position in the members 12 and 13, 30 and 31, but are also backed up by these members, and no twisting or tilting operation can be experienced as the cutter tool severs the coupling end of the scoop to divide the scoop body into the independent halves.

In the operation of pulling the scoop halves from the sides of the tape, the tool 20 remains momentarily in the position between the scoop halves.

It will be understood that the construction shown in Fig. 5, may be applied to a single scoop removal, as the structure diagrammatically illustrated is not for the purpose of showing the removal of two scoops, but to show a simpler apparatus or tool structure for accomplishing the desired result. In other words, in Fig. 5, the two parts 12 and 23, and 13 and 24 have been combined as one.

Having fully described my invention, what I claim as new and desire to secure by Letters Patent is:

1. The method of removing end scoops from stringers of separable fasteners, the scoops comprising mounting end portions and coupling end portions arranged beyond one edge of a stringer tape, which comprises supporting an end scoop with the coupling end portion thereof arranged in alinement with a severing tool, moving said tool through the central longitudinal part of the coupling end portion of the supported scoop to subdivide the entire coupling end portion beyond the tape edge, thus dividing the scoop into independent scoop halves disposed at opposite sides of the tape, and then moving the scoop halves away from side surfaces of the tape in the complete removal of the scoop from said tape.

2. The method of removing end scoops from stringers of separable fasteners, the scoops comprising mounting end portions and coupling end portions arranged beyond one edge of a stringer tape, which comprises supporting an end scoop between relatively movable jaw members engaging the mounting end portions of the scoop at opposite sides of the stringer tape, leaving the coupling end portion of the scoop arranged beyond and perpendicularly to said jaw members, then splitting the coupling end portion of the scoop centrally and in alinement with and up to the tape edge to divide the scoop into independent scoop halves disposed at opposite sides of the tape, and then moving said jaw members away from side surfaces of the tape in displacing the scoop halves from the tape.

3. The method of removing end scoops from stringers of separable fasteners, the scoops comprising mounting end portions and coupling end portions arranged beyond one edge of a stringer tape, which comprises supporting an end scoop between relatively movable jaw members engaging the mounting end portions of the scoop at

opposite sides of the stringer tape, leaving the coupling end portion of the scoop arranged beyond and perpendicularly to said jaw members, then splitting the coupling end portion of the scoop centrally and in alignment with and up to the tape edge to divide the scoop into independent scoop halves disposed at opposite sides of the tape, then moving said jaw members away from side surfaces of the tape in displacing the scoop halves from the tape, and then removing the scoop halves from said jaw members.

4. The method of removing end scoops from stringers of separable fasteners, the scoops comprising mounting end portions and coupling end portions arranged beyond one edge of a stringer tape, which comprises supporting the mounting end portion of an end scoop in members movable toward and from side surfaces of the stringer tape with the coupling end portion of said end scoop exposed beyond said members, then splitting the entire coupling end portion of the scoop arranged outwardly of the tape edge to divide the scoop into independent parts disposed at opposite sides of the stringer tape, and then moving said members away from side surfaces of the tape and pulling the scoop parts from the tape by said members.

5. The method of removing end scoops from stringers of separable fasteners, the scoops comprising mounting end portions projecting angularly from opposite sides of the stringer tape and coupling end portions arranged outwardly of the tape edge, which comprises moving jaw members, having sockets conforming with and adapted to receive the angular mounting portions of an end scoop, toward each other in engaging and supporting the mounting end portion of said scoop, then moving a knife through the coupling end portion of said supported scoop in alignment with the tape edge to completely subdivide the coupling end portion of said scoop beyond the tape edge to form independent scoop halves supported in said jaw members, and then separating said jaw members in forceable removal of the scoop halves from opposite side surfaces of said stringer tape.

6. The method of removing end scoops from stringers of separable fasteners, the scoops comprising mounting end portions projecting angularly from opposite sides of the stringer tape and coupling end portions arranged outwardly of the tape edge, which comprises moving jaw members, having sockets conforming with and adapted to receive the angular mounting portions of scoops of a stringer, toward each other in engaging and supporting the mounting end portions of said scoops, then moving severing means through the coupling end portions of said supported scoops in alignment with the tape edge to completely subdivide the coupling end portions of said scoops beyond the tape edge to form independent scoop halves of each scoop supported in said jaw members, and then separating said jaw members in forceable removal of the scoop halves from opposite side surfaces of said stringer tape.

7. The method of removing end scoops from stringers of separable fasteners, the scoops comprising mounting end portions projecting angularly from opposite sides of the stringer tape and coupling end portions arranged outwardly of the tape edge, which comprises moving jaw members, having sockets conforming with and adapted to receive the angular mounting portions of scoops of a stringer, toward each other in engaging and supporting the mounting end portions of said

scoops, then moving severing means through the coupling end portions of said supported scoops in alignment with the tape edge to completely subdivide the coupling end portions of said scoops beyond the tape edge to form independent scoop halves of each scoop supported in said jaw members, then separating said jaw members in forceable removal of the scoop halves from opposite side surfaces of said stringer tape, and then removing the scoop halves from said jaw members.

8. An apparatus for removing end scoops from separable fastener stringers, comprising jaw members movable toward and from each other, adjacent surfaces of the jaw members having sockets for receiving that part only of a scoop arranged at opposite side surfaces of the stringer tape, leaving the coupling end portion of the scoop exposed at one side surface of said jaw members beyond the tape edge, a knife movable toward and from the coupling end portion of a scoop supported in said jaw members to sever the entire coupling end portion of the scoop beyond the tape edge to form of the scoop independent scoop halves, and said scoop halves being removed from side surfaces of the stringer tape by movement of said jaw members away from each other.

9. An apparatus for removing end scoops from separable fastener stringers, comprising jaw members movable toward and from each other, adjacent surfaces of the jaw members having sockets for receiving that part only of a scoop arranged at opposite side surfaces of the stringer tape, leaving the coupling end portion of the scoop exposed at one side surface of said jaw members beyond the tape edge, a knife movable toward and from the coupling end portion of a scoop supported in said jaw members to sever the entire coupling end portion of the scoop beyond the tape edge to form of the scoop independent scoop halves, said scoop halves being removed from side surfaces of the stringer tape by movement of said jaw members away from each other, said jaw members being movable angularly to each other and to side surfaces of the stringer tape in engaging a scoop, and the jaw members being moved perpendicularly to side surfaces of the tape in removal of the scoop halves from the tape.

10. The herein described means for removing end scoops from separable fastener stringers, said means comprising a pair of jaw members movable toward and from each other, the jaw members having sockets opening through adjacent surfaces thereof in registering alignment, said sockets extending from said surfaces of the jaw members at such angles as to form between collective jaw members a combined socket of substantially V-cross sectional form, a shearing tool arranged in alignment with the adjacent surfaces of the jaw members when in abutting relationship, and said jaw members being movable away from each other in a common plane and at right angles to adjacent surfaces of said jaw members.

11. The herein described means for removing end scoops from separable fastener stringers, said means comprising a pair of jaw members movable toward and from each other, the jaw members having sockets opening through adjacent surfaces thereof in registering alignment, said sockets extending from said surfaces of the jaw members at such angles as to form between collective jaw members a combined socket or substantially V-cross sectional form, a shearing tool arranged in alignment with the adjacent surfaces of the jaw members when in abutting relationship, said

jaw members being movable away from each other in a common plane and at right angles to adjacent surfaces of said jaw members, and said jaw members being movable toward each other at an inclination substantially common with the inclination of the sockets in said jaw members.

12. In apparatus of the class described, a scoop engaging and supporting mechanism comprising a pair of jaw members movable toward and from each other, adjacent surfaces of the jaw members collectively forming a scoop receiving socket opening through one surface of each of said jaw members, said scoop and jaw members having relative movement for engagement of the jaw members with a scoop, and said jaw members being movable into open or separated position in a common plane perpendicular to the adjacent surfaces of said jaw members.

13. In apparatus of the class described, a scoop engaging and supporting mechanism comprising a pair of jaw members movable toward and from each other, adjacent surfaces of the jaw members collectively forming a scoop receiving socket opening through one surface of each of said jaw members, said scoop and jaw members having relative movement for engagement of the jaw members with a scoop, said jaw members being movable into open or separated position in a common plane perpendicular to the adjacent surfaces of said jaw members, one side of the jaw members in alignment with adjacent surfaces thereof having a kerf, and a knife movable toward and from the kerf of said jaw members when the latter are in closed position.

14. In apparatus of the class described, a scoop engaging and supporting mechanism comprising a pair of jaw members movable toward and from each other, adjacent surfaces of the jaw members collectively forming a plurality of scoop receiving sockets, each opening through one surface of both

of said jaw members, said scoops and jaw members having relative movement for engagement of the jaw members with a plurality of scoops, and said jaw members being movable into open or separate position in a common plane perpendicular to the adjacent surfaces of said jaw members.

15. In apparatus of the class described, the combination with a tool for severing an article into separate parts, of means engaging and supporting opposed side portions of the article in the operation of severing the same into separate parts, said means comprising members movable toward and from each other, and said members having sockets forming a gripping engagement with separate severed parts of said article in separation of said members.

16. In apparatus of the class described, the combination with a tool for severing an article into separate parts, of means engaging and supporting opposed side portions of the article in the operation of severing the same into separate parts, said means comprising members movable toward and from each other, said members having sockets forming a gripping engagement with separate severed parts of said article in separation of said members, and means for removing the separate parts of the article from the sockets of said members.

17. In apparatus for removing end scoops of separable fastener stringers employing tapes with scoops spaced longitudinally thereof, the combination with means for dividing a scoop into separate parts disposed at opposite sides of the tape of the stringer, of means for engaging and supporting a scoop in the operation of severing the same into separate parts, and said means being movable relatively to the stringer tape in removing the separate parts from said tape.

LOUIS H. MORIN.
